CLAIM

The ornamental design for a combined bottle and cap, as shown and described.

DESCRIPTION

FIG. 1 is a perspective view of the combined bottle and cap embodying our new design;

FIG. 2 is a front elevational view of the combined bottle and cap shown in an exploded condition;

FIG. 3 is a left-side elevational view of the bottle alone;

FIG. 4 is a rear elevational view of the bottle alone;

FIG. 5 is a right-side elevational view of the bottle alone;

FIG. 6 is a top plan view of the bottle alone;

FIG. 7 is a bottom plan view of the bottle alone;

FIG. 8 is a top plan view of the cap alone; and,

FIG. 9 is a bottom plan view of the cap alone.

The bottle in FIGS. 3-7, and the cap in FIGS. 8 and 9 are shown separately for clarity of illustration.
